Patented Nov. 1, 1966

206,118

STOOL

Donald L. Bates, Columbus, Ind., assignor to Hamilton Cosco, Inc., Columbus, Ind., a corporation of Indiana

Filed Sept. 3, 1965, Ser. No. 86,831

Term of patent 14 years

(Cl. D15—8)

FIG. 1 is a front elevation of a stool showing my new design;

FIG. 2 is a side elevation thereof;

FIG. 3 is a plan view thereof;

FIG. 4 is a rear elevation thereof; and

FIG. 5 is a horizontal section taken on the line 5—5 of FIG. 1.

The side opposite that shown in FIG. 2 has the appearance as that shown in FIG. 2.

I claim:

The ornamental design for a stool, as shown and described.
